ELISHA F. BRITTINGHAM, OF LOS ANGELES, CALIFORNIA, ASSIGNOR TO SARGENT & COMPANY, OF NEW HAVEN, CONNECTICUT

LOCK STRIKE

Application filed February 24, 1928. Serial No. 256,620.

This invention relates to a lock strike, and more particularly to an improved form of lock strike and improved manner of securing the same to the jamb of a door or the like.

5 The lock strike of this invention, while not limited to use with a spring latch or lock to be mounted on an outer surface of a door, is especially useful in connection with such a form of lock. According to the prior art, the usual lock strike used in connection with a lock of this type is provided with a bolt-receiving body which is mortised into an outer face of a door jamb or the like, and is provided with a laterally extending 10 flange or other portion which is mortised into an inner face of the door casing. Such strikes are usually secured to the door casing by means of screws which pass from the exterior of the strike through openings in 15 the body thereof and into the door casings. In order to provide room for passing the screw or screws through the body of the strike, the usual strike is provided with a much larger portion engaging the outer face 20 of the door jamb than would otherwise be necessary and requiring, in most instances, that this portion be mortised into the jamb.

In order to provide a lock strike having a more slight appearance than the usual strike, it is proposed in the present invention to provide a strike which may be mounted on the jamb of the door without the use of exposed fastening means.

25 Another object of the invention is to provide a form of lock strike which may be mounted on the jamb of a door or the like without the necessity of mortising the strike into the jamb or other support.

30 A further object of the invention is to provide a lock strike in which there is provided a concealed but efficient means for securing the strike to the jamb of the door.

To these and other ends, the invention 35 consists in the novel features and combina-

tion of parts to be hereinafter described and claimed.

In the drawings,

Fig. 1 is a fragmentary view of a door and a door casing showing a preferred embodiment of my invention mounted thereon;

Fig. 2 is a view along line 2—2 of Fig. 1;

Fig. 3 is a cross-sectional view along line 3—3 of Fig. 2; and

Fig. 4 is an end view of my improved lock 55 strike, taken in a direction similar to Fig. 3.

Referring now to the drawings in which I have shown a preferred embodiment of my invention, the reference numeral 5 indicates in general a portion of a door having 60 mounted thereon a lock casing 6, which may be of any usual or preferred type, and which will not therefore be described herein in detail, the lock casing 6 being secured to the door 5 by suitable means, as for example, 65 screws 7, and being provided with a latch bolt 8, and the usual thumb turn 9 for retracting the bolt.

Adjacent the door 5 is a door jamb 10, having mounted thereon my improved form 70 of lock strike 11, which is provided with a bolt retracting face 12, and a bolt receiving opening 13. Strike 11 is provided with a relatively narrow face 14, which abuts against the outer face 15 of jamb 10, and a 75 rearwardly extending flange 16, which may be secured to the inner face 17 of jamb 10 by suitable means, as, for example, screws 18. The side of strike 11 abutting against the face 15 of jamb 10 is preferably solid 80 and passing from the interior of strike 11 through this solid portion and into jamb 10 is a suitable fastening means herein shown in the form of screw 19. As shown in the drawings, the face 14 is of less width than the depth of the bolt receiving opening 13 and the wall 20 of strike 11 extends outwardly from jamb 10 substantially at an acute angle.

85 In use, my improved form of lock strike 90

may be placed in a suitable position on the jamb of a door opposite the lock with the face 14 abutting the outer face of the jamb and the screw, or other fastening means, 19 passed through the opening in the strike 20 body provided for that purposes and into the jamb. It will be seen from Figure 1 of the drawings that the screw 19 is entirely concealed when the door is closed. By extending wall 20 in a direction substantially 25 forming an acute angle with the face of the door jamb, it is possible to mount the strike on the edge portion of the jamb where it will not interfere with any beading, molding, or other ornamental portion 30 of the jamb, while at the same time the face 14 forms a suitable support for the strike.

By providing the lock strike with a solid portion at the back of the bolt opening and 20 passing a fastening member through this portion into the face of the door jamb, I am enabled to omit the laterally extending flange usually provided at the face of the door jamb through which the fastening 25 members are ordinarily passed. This flange must be mortised into the face of the door jamb and by omitting that element I provide a lock strike which may be secured in place much more easily, and at the same 30 time will not deface the door jamb.

While I have shown a preferred embodiment of my invention, it is to be understood that the same is not to be limited to all the details shown but is capable of modification 35 and variation within the spirit of the invention and the scope of the appended claims.

What I claim is:

1. In a lock strike adapted to be secured 40 to a jamb of a door or the like, a pair of opposed walls between which the bolt of a lock or the like may be received, one of said walls being substantially parallel to the face of the jamb and the other of said 45 walls extended at an acute angle thereto, said last named wall being provided with an outer face of less width than the width of the wall parallel to the face of the jamb, said face being adapted to abut against the 50 jamb of the door, and fastening means passing through said last named wall and into the jamb of the door.

2. In a lock strike adapted to be secured 55 to a jamb of a door or the like, a pair of opposed walls between which the bolt of a lock or the like may be received, one of said walls being substantially parallel to the face of the jamb and the other of said walls extended at an acute angle thereto, 60 said last named wall being provided with an outer face of less width than the width of the wall parallel to the face of the jamb, said face being adapted to abut against the jamb of the door, and fastening means passing 65 through said last named wall and the

jamb abutting face thereof and into the jamb of the door.

3. A lock strike adapted to be applied to a door jamb comprising an inner face portion abutting against and secured to the door jamb and an outer wall substantially parallel to said inner face portion and of greater width than said face portion, and a rear wall inclined rearwardly and outwardly from the door jamb and connecting said outer wall and face portion.

In witness whereof, I have hereunto set my hand this 2d day of February, 1928.

ELISHA F. BRITTINGHAM.
